UNITED STATES PATENT OFFICE.

AMÉDÉE VICTOR JOSEPH GUILLET, OF PARIS, FRANCE.

STROBOSCOPE WITH VIBRATING CORD.

Application filed March 10, 1924, Serial No. 698,303, and in France March 22, 1923.

This invention relates to stroboscopes. The requirements of mechanical stroboscopes are that flashes should be produced having a frequency which remains constant 5 at a predetermined value N for as long a time as is desired and further that there be a possibility of varying this frequency N easily and continuously. It is further necessary that the value N can be read directly from 10 the stroboscope or obtained from a simple formula.

A stroboscope having a perforated disc does not comply with these conditions, in particular, the braking of the motor on the 15 shaft of which the disc is mounted, renders the stroboscopic operation delicate. With a tuning fork, a fixed flash frequency is indeed obtained but the continuous simultaneous and equal displacement of two identical 20 masses along the arms of such tuning fork cannot be done without difficulty. On the other hand the field of frequency which is thus available with the same tuning fork, is relatively limited.

According to the present invention a stroboscope is provided in which the vibratory member is composed of a vibrating cord or string having a sustained vibratory movement. A stroboscope formed under these 30 conditions allows of its being operated with full convenience and precision over a considerable field of flash frequency.

It is essential that the vibrating cord shall be mounted in such a way that its vibratory 35 movement is maintained without trouble or disturbance. Various arrangements may be utilized for this object. The annexed drawing shows three of them by way of examples.

Fig. 1 is an elevation of one form of 40 stroboscope.

Figs. 2 and 3 are modifications of the vibratory means for such a stroboscope.

Fig. 4 shows a means for adjusting the tension of the stroboscope cord or wire.

A steel piano wire a selected so as to be 45 free from any twist and curvature is firmly held at its ends in two grips a^1 and a^2 (Fig. 1) arranged on a frame b mounted on a base b^1 provided with levelling screws. One of 50 the grips a^1 is fixed, the other a^2 is movable so as to allow the tension of the cord to be varied as will be hereinafter shown. Opposite the cord a an electro-magnet c is arranged which receives current set up or cut 55 out by the wire itself each time it passes through its position of equilibrium.

The contact must be placed at the extreme end of the cord, that is to say in immediate proximity to its point of attachment. In Fig. 1 the movable contact is shown at d and formed by an envelope of platinum, tungsten, carbon or the like surrounding the cord, and the fixed contact shown at e is carried by an accurate micrometer screw e^1 , which allows the degree of contact between d and e 60 to be regulated.

The total work of the forces set up between the cord and the electromagnet is positive and is thus a driving one if the circuit is established on the passage through the 70 position of equilibrium when the cord moves away from the electromagnet, due to the electric and magnetic dissymmetrical forces which accompany the setting up and breaking of the current.

It is still more efficient to employ the cord a for closing and opening the circuit of a small transformer f (Fig. 2) the secondary current of which excites the electro-magnet c , the acting element of the wire being permanently magnetized by an auxiliary circuit a^3 wound on the electromagnet.

Further the secondary current may in other cases be led into the cord a , which is arranged to be oscillatable perpendicularly 85 to the lines of force of a magnet g surrounding its centre part (Fig. 3).

The movement of the cord being thus sustained by one of the means hereinbefore described, flashes are produced by projecting 90 on to a plate h , which is perforated as with a hole or a slot h^1 , the image from a luminous source (arc or incandescent filament) and fixing in the middle of the cord an extremely light plate i also perforated with a hole or slot i^1 corresponding with the hole or slot in the plate h . The two apertures h^1 and i^1 , being opposite one another when the cord is at rest, will be in this same position, when the cord will vibrate, each time that the cord will 100 pass through its position of equilibrium, that is to say twice per period. The flash frequency will therefore be $2N$ if the cord frequency is N .

The modification of this frequency by insensible degrees and over a considerable interval may be obtained by varying the tension of the cord.

For this purpose the grip a^2 of the cord is mounted (Fig. 4) on an internally threaded 110 socket k which may be displaced by means of a screw l provided with a large head carry-

ing divisions. It is thus easy to apply to the cord a tension varying continuously and over a wide interval and consequently to bring the frequency N to the value required by the 5 stroboscopic adjustment desired.

The field of frequencies thus explored may lie over several octave intervals and is sufficient for practical purposes. But there is no objection to arranging the cord and the accessory members in such a way as to utilize 10 successively various lengths of cord or still to mount on the same frame several cords actuated by the same electro magnet, adapted to be arbitrarily substituted one for another.

15 If it is desired to use a gut string or a string of a non-magnetic metal, the third method of sustaining the vibration hereinbefore described must be employed, or there must be arranged on the string at the point 20 of interaction a soft iron wire.

Stroboscopic harmony having been effected, the frequency is determined by utilizing the following formulæ:

$$25 \quad X^2 = (N_0^2 - N_1^2) \frac{n_x - n_0}{n_0 - n_1} + N_0^2$$

and

$$30 \quad X^2 = (N_0^2 - N_1^2) \frac{n_x - n_1}{n_0 - n_1} + N_1^2$$

in which X is the frequency desired, $n_0 - n_1$, $n_x - n_0$, and $n_x - n_1$ the displacements of the 35 divisions of the divided head l^1 when passing from the frequency N_0 to the frequency N_1 and from the frequency X to the frequency N_0 or the frequency N_1 .

The constant of the stroboscope

$$40 \quad \frac{N_0^2 - N_1^2}{n_0 - n_1}$$

may be determined either by the direct registration of N_0 and N_1 or still by placing the cord and the two diapason types given, in 45 stroboscopic equilibrium. The ascertaining of the positions, n_0 and n_1 , of the index must be further effected in both cases.

If the variations of the tension of the cord are such that the cord undergoes, in 50 the course of the operations, an appreciable permanent elongation, it is no longer possible to make use of the formulæ hereinbefore indicated.

It will then be necessary to connect the 55 cord or string firmly with the support by means of a dynamometer or a balance lever indicating the value of the tension for all given positions of the stretcher. The frequency N is then calculated by applying the 60 known formula giving the fundamental frequency of a stretched cord.

The frequency may also be modified by insensible degrees by continuous variations of the length of the cord by means of double 65 bridge sliding along the latter. When it is a

question of estimating a frequency producing a regular note like the hem of an axle, the stroboscope forming a cord siren allows of the tuning by beats.

What I claim is:

1. A stroboscope, comprising a frame, a vibrating cord, means for securing said cord at its ends to said frame, means, controlled by the vibrating cord, for producing stroboscopic flashes, electro-magnetic means for 75 sustaining the vibration of said cord and means, controlled by the vibrating cord, for supplying current to said electro-magnetic means.

2. A stroboscope, comprising a frame, a 80 vibrating cord, means for securing said cord at its ends to said frame, means, controlled by the vibrating cord, for producing stroboscopic flashes, electro-magnetic means adapted to sustain the vibration of said cord, and 85 contact means controlled by the cord.

3. A stroboscope, comprising a frame, a vibrating cord, means for securing said cord at its ends to said frame, means, controlled by the vibrating cord, for producing stroboscopic flashes, electro-magnetic means for 90 sustaining the vibration of said cord, together with contact members arranged at a point closely adjacent to one of the points of attachment of the cord, for the purpose 95 described.

4. A stroboscope, comprising a frame, a vibrating cord, means for securing said cord at its ends to said frame, means, controlled by the vibrating cord, for producing stroboscopic flashes, electro-magnetic means for 100 sustaining the vibration of said cord, and means, controlled by the vibrating cord, for supplying current to said electro-magnetic means, together with means for regulating at 105 will, by continuous degrees and within a wide range, the vibratory frequency of said cord.

5. A stroboscope, comprising a frame, a vibrating cord, means for securing said cord 110 at its ends to said frame, means, controlled by the vibrating cord, for producing stroboscopic flashes, electro-magnetic means for sustaining the vibration of said cord, and means, controlled by the vibrating cord, for 115 supplying current to said electro-magnetic means, together with means for regulating the vibratory frequency of said cord by adjusting the tension thereof.

6. A stroboscope, comprising, a frame, a 120 vibrating cord, means for securing said cord at its ends to said frame, means, controlled by the vibrating cord, for producing stroboscopic flashes, electro-magnetic means for 125 sustaining the vibration of said cord, and means, controlled by the vibrating cord, for supplying current to said electro-magnetic means, a screw stretcher device at one of the ends of the cord for adjusting the tension 130 of the cord.

7. A stroboscope, comprising, a frame, a vibrating cord, means for securing said cord at its ends to said frame, means, controlled by the vibrating cord, for producing stroboscopic flashes, electro-magnetic means for sustaining the vibration of said cord, and means, controlled by the vibrating cord, for supplying current to said electro-magnetic means, a screw stretcher device at one of the ends of the cord for adjusting the tension of the cord, an operating head on the stretcher device, and graduations on the head.
- 5 In testimony whereof I have signed my name to this specification.

AMÉDÉE V. J. GUILLET.
